UNITED STATES PATENT OFFICE.

NOBLE R. STREETER, OF BROOKLYN, NEW YORK.

WALL-PAPER.

SPECIFICATION forming part of Letters Patent No. 444,213, dated January 6, 1891.

Application filed February 15, 1889. Serial No. 299,998. (No specimens.)

To all whom it may concern:

Be it known that I, NOBLE R. STREETER, of the city of Brooklyn, in the county of Kings and State of New York, have made certain 5 new and useful Improvements in Wall-Paper; and I do hereby declare that the following is a full, clear, and exact description thereof, reference being had to the accompanying drawing, forming part of this specification.

Wall-paper as heretofore hung is put up in the roll in a continuous strip—one roll for the body of the paper, another for the border, and a third for the dado, if one is used. In 15 hanging it the body of the paper has to be laid onto the wall in a strip, commencing at the top and leaving a space for the border, which is then laid on. In case of use of a dado, the same is cut from another roll and placed at 20 the lower portion of each length. The dado is sometimes laid onto the bare wall and sometimes over the lower portion of the body of the paper, which is continued down to the surbase.

Now ceilings, particularly those of bed-rooms, are of a conventional height, usually nine, ten, or eleven feet between the cornice or angle of the ceiling and the top of the sur-base. My improvement therefore consists in 25 making a roll of wall-paper in which shall be contained strips, say, of either nine, ten, eleven feet, or other lengths, and on each of which strips shall be contained a length of wall-paper, together with a border at top and dado at the bottom of such strip. All the pa-30 per-hanger has, therefore, to do after obtain-ing the measurement of the wall between the angle of the ceiling or lower edge of the cor-

nice and the top edge of the surbase is to take a roll which has strips of that dimen- 40 sion, unroll a strip from off of the roll, cut it off, and paste it onto the wall, beginning at the top or end containing the border. The time consumed in thus hanging the wall-paper, border, &c., is very largely reduced over the 45 old method, in which last-mentioned method separate rolls were used and the paper cut off of each and laid on in sections. These strips in the roll may be made without the dado so as to furnish wall-paper with a border alone 50 in strips; or a dado can be used, leaving off the border. The latter may be desirable in case of a cornice being below the angle of the ceiling not conveniently permitting of the use of a border. 55

I claim—

1. As a new article of manufacture, a roll of wall-paper containing strips or lengths, each of which strips or lengths has combined 60 a border with the wall-paper, substantially as described.

2. As a new article of manufacture, a roll of wall-paper containing strips or lengths, each of which strips or lengths has combined 65 a dado with the wall-paper, substantially as described.

3. As a new article of manufacture, a roll of wall-paper containing strips or lengths, each of which strips or lengths has combined 70 a border and dado with the wall-paper, substan-tially as described.

NOBLE R. STREETER.
